DESIGN FOR A CAPE.

Design No. **6,642**, dated May 6, 1873

UNITED STATES PATENT OFFICE.

MARTIN LANDENBERGER, JR., OF PHILADELPHIA, PENNSYLVANIA.

DESIGN FOR A CAPE.

Specification forming part of Design No. **6,642**, dated May 6, 1873; application filed April 8, 1873.

To all whom it may concern:

Be it known that I, MARTIN LANDENBERGER, Jr., of Philadelphia, Pennsylvania, have invented a Design for a Garment, of which the following is a specification:

The garment, which is clearly represented by the figure in the accompanying drawing, has the usual semicircular outline, is cut straight across at the top with a recess, *a*, for the neck-band, and is in the present instance split or slashed at the back. The hood *A* is triangular with a rounded elongation, *b*, at the bottom, the latter being ornamented by a deep fringe, *c*, similar to that which forms the border of the garment and of the neck-band *a*. The hood is ornamented by a double row of gimp-like fringe, *d*, and by tassels *e* and *f*. Cords and tassels *g* are also suspended from

the neck-band. The body of the garment is composed of vertically-striped fabric and the hood of the same fabric, but with the stripes extending transversely across the same.

Irrespective of the color employed, I claim—

1. The design for the hood *A*, having the outline, substantially as shown and described.
2. The design for a vertically-striped circular garment having a horizontally-striped hood, substantially as described and represented.

In testimony whereof I have signed my name to this specification in the presence of two subscribing witnesses.

MARTIN LANDENBERGER, JR.

Witnesses:

J. J. BUCHEY,
JNO. JAY WARD.
